INTERLOCKING FINGER RING

Daniel Shiman, Maplewood, N.J., assignor to Shiman Manufacturing Company, Inc., Newark, N.J., a corporation of New York

Filed July 14, 1967, Ser. No. 7,800

Term of patent 14 years

Int. Cl. D11—01
U.S. Cl. D45—10

FIG. 2.

FIG. 4.

FIG. 5.

FIGURE 1 is a top perspective view of an interlocking finger ring showing my new design;

FIGURE 2 is a side elevation thereof;

FIGURE 3 is a top plan view thereof;

FIGURE 4 is an end elevation thereof;

FIGURE 5 is an exploded view thereof, the secondary ring is raised and the primary ring is shown in vertical cross-section;

FIGURE 6 is an enlarged section taken on line 6—6 of FIGURE 3.

The characteristic feature of my design for an interlocking finger ring, consisting of a primary ring with an interfitting secondary ring, resides in the combination of the following features. The primary ring has two sections that are separated by a gap which has a uniform width around the circumference of the primary ring. The circumferential peripheral surface of each of the primary ring sections is divided into an inner band bordering the gap and an outer band. Each outer band is oriented so that any plane tangential to the outer band is parallel to the axis of the ring. Each outer band has parallel ridges in it which extend across the band transversely to the axis of the ring. Each inner portion is sloped concavely and inwardly toward the axis of the ring. The secondary ring, situated within the gap between the outer ring sections, holds gems.

I claim:

The ornamental design for an interlocking finger ring, as shown and described.
